RECEPTACLE COVER

Clemens J. Bax, Kansas City, Mo.

Application May 16, 1950, Serial No. 162,234

10 Claims. (Cl. 220—46)

1

This invention relates to receptacle covers and more particularly to an improved engageable and releasable type for quick access to the receptacle.

An object of the present invention is to provide an improved cover with engageable clamping hooks to be clamped on a receptacle flange by having a single manual control within a dust tight chamber whereby the cover may be quickly engaged or disengaged.

Another object of the present invention is to provide a cover having a top plate, bottom plate and connecting sides forming a dust protective enclosure chamber for the reception of the controls connected to the clamping hooks, the hooks projecting through the sides of the cover and engaging the flange of a receptacle. The receptacle may be a conveyor trough or any type of mixing bin as commonly employed by the milling industry.

With these objects in view the invention is better understood by the illustrated views of the accompanying drawings, the following description and more fully pointed out in the appended claims.

In the drawing:

Figure 1 is a plan view of a fragment of the improved cover with the hinged type hook.

Figure 2 is a fragmentary view in elevation of the improved hinged type hook with broken portions of the cover and a receptacle flange being shown.

Figure 3 is a perspective view of the cover removed from a receptacle illustrating the sides and bottom thereof.

Figure 4 is a fragmentary view of one end of the cover with portions broken away to illustrate one end of the latch bar with the respective anchor therefor.

Figure 5 is a perspective view of the improved cover clamped on a portion of a screw conveyor trough.

Figure 6 is a perspective view of a portion of a screw conveyor illustrating a bolted cover and a ledge attached thereto for the improved latch bar.

Figure 7 is a bottom view of the cover with the bottom member thereof removed to illustrate the sliding latch members and clamp hooks in latched position. The unlatched positions are illustrated by dotted lines.

Figure 8 is an enlarged fragmentary view illustrating the sliding members having a hook on the end thereof in an unlatched position for engaging a receptacle flange.

The receptacle cover may be constructed of any of the well known materials and as illustrated

5 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

2

comprises a top rectangular plate member 9, side enclosure members 10, end enclosure members 11, and bottom dust protective plate 12. Plate member 12 is rectangular and attached to end enclosure members 11 by screws 13 engaging holes 14.

The side enclosure members 10 are set back from the bottom edge of the top member 9 to provide room for flange gaskets 15 contacting the receptacle flanges 16. The end enclosure members 11 are set back from the bottom edges of the top member 9 to provide for recessed gaskets 17. The recessed gaskets fit on the top of the latch anchor bars 18 secured to bolted cover plate 19 or bolted cross bar 20. The end enclosure members 11 are tapered at 21 and are set back sufficiently to have the outer edges thereof register with the inner edges of the recessed gaskets 17.

The top member 9 is provided on the bottom 20 thereof with a series of spaced parallel lateral slots or recesses 22 extending from the inner portion of the member 9 to the outer edges thereof. A lateral latch slide bar 23 as illustrated in Figure 8 is provided in each recess 22 and attached 25 to the member 9 by countersunk head screws 24 through the elongated slots 25 in the bars 23. The outer end of each lateral latch slide bar 23 projects beyond the respective recess 22 and member 9 forming a hook by having the ends 27 bent 30 downward into a reverse curve at 26 and the end 27 thereof tapering in a diverging direction from the main portion of the bar 23 forming a clamp hook. The inner ends of the lateral latch slide bars 23 have offset bends 28 therein and extend 35 to the lower surface of the top rectangular plate member 9 where they are integrally joined in pairs by longitudinal guide bars 29.

A longitudinal latch bar 30 is located below the top rectangular plate member 9 and extends 40 through the longitudinal center thereof, through the ends 11, and projects therebeyond at 31 and 32 to latch beneath the latch anchor bars 18, the bar 30 is provided with longitudinal slots 33 and keeper bolts 34 for slidable engagement there- 45 with.

Toggle members 35 have one end of each pivoted at 36 on the longitudinal latch bar 30 and the opposite end of each toggle bar 35 pivoted at 37 on the juncture of the lateral slide bars 23 with 50 longitudinal guide bars 29.

A manually operated lever 38 is pivoted on the pin 39 recessed in the top member 9 and held in bearing members 40 secured in recessed top rectangular plate member 9.

The lower end portion of the lever 38 is slotted

to receive pin 41 secured to ears 42 mounted on longitudinal latch bar 30. The pins 39 and 41 are preferably mounted near the center of the top plate member 9 and the lever 38 is pressed into the slot 43 of the top member 9 when the lateral latch bars 23 with hook ends 27 are moved toward the longitudinal center of the cover in a latched position. A keeper plate 44 is pivoted at 45 and holds the latch bar 38 in the cover when the cover is latched and clamped on the receptacle flanges.

A different form of hook 46 is illustrated in Figures 1 and 2 and is hinged at 47 on slide bar 48, the lateral slide bar 48 moves in recess 49 and is connected to the hook 47 and provided with a spring 50 to normally raise the hook in an upward position. The hook 46 when in a raised position butts against plate 51 held to cover top member 52 by screw 53, the lower end 54 of the plate 51 is positioned to pull the hook downward into a latching position around the receptacle flange 16 when the slide bar 48 is moved toward the longitudinal center of the cover plate 52, side members 55 are similar to side members 10 and receive a bottom dust protective plate 56 which is similar to bottom dust protective plate 12. The plate 51 is recessed in the top member 52 at 57 and a slot 58 extends from the recess 57 to the outer edge of the top member 52 for the hook 46 to move therein. The spring 50 has projected ends 59 anchored on the slide bar 48 and the center portion 60 of the spring is anchored on the back of the hook at 61.

In the operation the longitudinal slide latch bar 30 in the open position has end 32 moved to a flush position with the end member 11 at the inner edge of the gasket 17 and the opposite end 31 slides outward to the outer edge of the respective gasket 17. The longitudinal latch bar 30 moves on keeper bolts 34 by means of the longitudinal slots 33 and the toggle members 35 push outward in a lateral manner to the slide bars 23, the lateral slide bars 23 moving in recesses 22, on screws 24 by means of slots 25 move the hooks with the reversed bends 26 and ends 27, outward to a released position as illustrated in Figure 8. The end of the cover containing the longitudinal latch bar end 32 is raised upward first and the cover is removed by withdrawing latch bar end 31 from the latch anchor bar 18. To apply the cover to the receptacle flange the movements are reversed and the hooks are drawn and wedged against the edges of the flanges 15 and tightened against the gaskets 15.

When the area around the receptacle is crowded or congested with other pieces of equipment it is often necessary to use the hinged hook as illustrated in Figure 2 it being obvious that the other members work the same as heretofore described except that the hook swings upward on the hinge to butt against the plate 51 within the recess 57 by means of the spring 50.

What I claim as new and desire to secure by Letters Patent is:

1. A rectangular plate cover for a flanged receptacle, side members, end members, said side and end members secured to said cover and spaced from the edges thereof, a single slide latch bar, said slide latch bar being slidably attached to said cover, said slide latch bar having the ends thereof projected through said end members attached to said cover, a manually operated lever attached to said cover, said lever attached to said slide latch bar and having a means for withdrawing one end of said slide latch bar within said end members, plural transverse slide bars,

guide bars connecting said transverse slide bars in pairs, said guide bars being parallel with and spaced from said slide latch bar, toggle members, said toggle members being pivoted to said slide latch bar and said guide bars, said toggles forcing said guide bars to and from said slide latch bar whereby one end of said slide latch bar may be drawn within the respective end members attached to said cover by said lever, said slide bars projecting through the said side members of said cover, and latch members on the ends of said slide bars outside of said side members to releasably engage said cover on a flange receptacle.

2. The combination as recited in claim 1 including a dust protective plate, said dust protective plate attached to said side members and enclosing the major portion of said bars between said plate cover and said dust protective plate to keep out all dust from the enclosure.

3. A rectangular plate cover for a flanged receptacle, a single longitudinal slide latch bar, said slide latch bar being slidably attached to said cover, said longitudinal latch bar having the ends thereof moved toward the ends of said cover, a manually operated lever attached to said cover, said lever attached to said longitudinal slide latch bar for moving said longitudinal slide latch bar longitudinally on said plate cover, plural transverse slide bars, longitudinal guide bars connecting said transverse bars, said longitudinal guide bars being parallel with said longitudinal slide latch bar, toggle members, said toggle members being connected to said slide latch bar and said longitudinal guide bars, said toggles forcing said longitudinal guide bars to and from said longitudinal slide latch bar whereby when said longitudinal slide latch bar is moved on said cover, said plural transverse slide bars will move, latch members on said transverse latch slide bars, said transverse latch slide bars projecting beyond the edges of said cover and the latch members on the ends of said transverse latch slide bars movable outside of said cover.

4. A cover for a receptacle comprising a plate having a single longitudinal latch bar supported from the underside thereof for longitudinal movement, spaced pairs of parallel latch slide bars supported from said plate on opposite sides of said latch bar for transverse movement, links connecting said latch slide bars to said latch bar for imparting transverse movement to said latch slide bars in response to longitudinal movement of said latch bar, said latch bar and said latch slide bars having ends projectable beyond the edges of said plate for engagement with a receptacle and retaining said plate thereon, longitudinal outward movement of said latch bar to a cover retaining position causing inward movement of said latch slide bars to cover retaining positions.

5. A cover for a receptacle comprising a plate having a single longitudinal latch bar supported from the underside thereof for longitudinal movement, spaced pairs of parallel latch slide bars supported from said plate on opposite sides of said latch bar for transverse movement, links connecting said latch slide bars to said latch bar for imparting transverse movement to said latch slide bars in response to longitudinal movement of said latch bar, said latch bar and said latch slide bars having ends projectable beyond the edges of said plate for engagement with a receptacle and retaining said plate thereon, longitudinal outward movement of said latch bar to a cover retaining position causing inward movement of said latch slide bars to cover retaining

positions, a lever extending through said plate and pivotally connected to said latch bar for imparting longitudinal movement to the same.

6. A cover for a receptacle comprising a plate having a single longitudinal latch bar supported from the underside thereof for longitudinal movement, spaced pairs of parallel latch slide bars supported from said plate on opposite sides of said latch bar for transverse movement, links connecting said latch slide bars to said latch bar for imparting transverse movement to said latch slide bars in response to longitudinal movement of said latch bar, said latch bar and said latch slide bars having ends projectable beyond the edges of said plate for engagement with a receptacle and retaining said plate thereon, longitudinal outward movement of said latch bar to a cover retaining position causing inward movement of said latch slide bars to cover retaining positions, said plate being provided with spaced parallel recesses in the underside thereof, said latch slide bars having offset end portions guidingly received in said recesses.

7. A cover for a top flanged receptacle, said cover having spaced parallel recesses therein, spaced parallel bars slidably mounted in said recesses, a dust-tight gasket on said cover, said dust-tight gasket passing over said recesses and enclosing portions of said bars in said recesses, latch hooks formed on outer ends of each of said bars, said latch hooks being tapered to wedge on the flanged receptacle, means connecting said hooks for a single manual control to open and close said hooks on the flanges of the receptacle, said hooks extending from the sides of said cover, a single longitudinal latch bar, said longitudinal latch bar passing through the ends of said cover, and said longitudinal latch bar connected to said means for a single manual control.

8. A rectangular plate cover for a flanged receptacle, a single longitudinal slide latch bar slidably attached to said cover, said latch bar having ends thereof movable towards ends of said cover, a manually operable lever attached to said cover and said latch bar for moving said latch bar longitudinally of said cover, a plurality of longitudinally spaced transverse slide bars, longitudinal guide bars connecting longitudinally adjacent pairs of slide bars, said guide bars being parallel to and closely adjacent said latch bar, toggle members connecting said latch bar and said guide bars, said toggles being adapted to force said guide bars towards and away from said latch bar upon longitudinal movement of said latch bar to effect movement of said slide bars, latch members on ends of said slide bars remote from said guide bars, said latch members being disposed beyond side edges of said cover and engageable with the flanged receptacle.

9. A rectangular plate cover for a flanged receptacle, a single longitudinal slide latch bar slidably attached to said cover, said latch bar having ends thereof movable towards ends of said cover, a manually operable lever attached to said cover

and said latch bar for moving said latch bar longitudinally of said cover, a plurality of longitudinally spaced pairs of transversely extending slide bars, longitudinal guide bars connecting longitudinally adjacent pairs of slide bars, said guide bars being parallel to and closely adjacent said latch bar, toggle members connecting said latch bar and said guide bars, said toggles being adapted to force said guide bars towards and away from said latch bar upon longitudinal movement of said latch bar to effect movement of said slide bars, latch members on ends of said slide bars remote from said guide bars, said latch members being disposed beyond side edges of said cover and engageable with the flanged receptacle, said latch members being in the form of tapered hooks.

10. A rectangular plate cover for a flanged receptacle, a single longitudinal slide latch bar slidably attached to said cover, said latch bar having ends thereof movable towards ends of said cover, a manually operable lever attached to said cover and said latch bar for moving said latch bar longitudinally of said cover, a plurality of longitudinally spaced transverse slide bars, longitudinal guide bars connecting longitudinally adjacent pairs of slide bars, said guide bars being parallel to and closely adjacent said latch bar, toggle members connecting said latch bar and said guide bars, said toggles being adapted to force said guide bars towards and away from said latch bar upon longitudinal movement of said latch bar to effect movement of said slide bars, latch members on ends of said slide bars remote from said guide bars, said latch members being disposed beyond side edges of said cover and engageable with the flanged receptacle, longitudinal outward movement of said latch bar to a cover retaining position causing inward movement of said slide bars to cover retaining positions.
